CLAIM

(21) Appl. No.: **29/187,511**

The ornamental design for elements of a hood for a snowmobile, as shown and described.

(22) Filed: **Aug. 4, 2003**

DESCRIPTION

(30) **Foreign Application Priority Data**

Feb. 3, 2003 (CA) 2003-101953

FIG. 1 is a perspective illustration, from the front and left side, of elements of a hood for a snowmobile according to our design;

(51) LOC (7) Cl. **12-14**

FIG. 2 is a top plan view thereof;

(52) U.S. Cl. **D12/7**

FIG. 3 is a left side elevational view thereof;

(58) Field of Search D12/7; 180/182-186, 180/190, 68.2, 69.21; 296/193.12, 901.01

FIG. 4 is a right side elevational view thereof;

FIG. 5 is a front elevational view thereof; and,

FIG. 6 is a rear elevational view thereof.

(56) **References Cited**

In FIGS. 1-6, broken lines showing structure are for illustrative purposes only and form no part of the claimed design.
